UNITED STATES PATENT OFFICE.

CHARLES A. PETERSON, OF HOT SPRINGS, SOUTH DAKOTA.

CUT-OFF VALVE.

SPECIFICATION forming part of Letters Patent No. 619,088, dated February 7, 1899.

Application filed March 17, 1898. Serial No. 674,199. (No model.)

To all whom it may concern:

Be it known that I, CHARLES A. PETERSON, of Hot Springs, in the county of Fall River and State of South Dakota, have invented a 5 new and Improved Cut-Off Valve, of which the following is a full, clear, and exact description.

The invention relates to cut-off valves for steam-engines; and its object is to provide 10 a new and improved valve which is simple and durable in construction, very effective in operation, completely balanced, arranged to properly and automatically govern the engine according to the load, and adapted for use on 15 ordinary steam-engines now constructed to render the same almost equal to high-grade engines, such as the Corliss and the like.

The invention consists of novel features and parts and combinations of the same, as 20 will be described hereinafter, and then pointed out in the claims.

Reference is to be had to the accompanying drawings, forming a part of this specification, in which similar characters of reference indicate 25 corresponding parts in all the figures.

Figure 1 is a side elevation of the improvement as applied. Fig. 2 is a sectional plan view of the same on the line 2 2 of Fig. 1. Fig. 3 is a like view of the same on the line 30 3 3 of Fig. 1. Fig. 4 is a transverse section of the same on the line 4 4 of Fig. 1. Fig. 5 is a side elevation of the main valve with the packing-plate removed to show cavity for the packing-springs. Fig. 6 is an inner face view 35 of the packing-plate, and Fig. 7 is a plan view of the main valve.

The engine on which the valve is applied is provided with the usual cylinder A, in which reciprocates the piston B, connected with the 40 main driving-shaft C in the usual manner. The cylinder A is provided with the inlet-ports a and b and an exhaust-port c, the said ports registering with ports d e f, respectively, formed in the valve-body D and held within 45 a steam-chest E, having a steam-inlet pipe E' connected with a suitable source of steam-supply, such as a boiler or the like. An exhaust-pipe E² leads from the exhaust-port c (see Fig. 4) to carry off the exhaust-steam.

50 The valve-body D is formed with a cylindrical valve-seat for the cylindrical oscillating main valve F, made hollow to receive a

cut-off valve G, likewise made cylindrical and arranged to oscillate, the said cut-off valve being mounted to turn on a hollow valve-stem H 55 for the main valve F, and through which passes the valve-stem I for the cut-off valve G, the said valve-stems I and H being mounted to turn independently of each other, the stem H being controlled from the eccentric of 60 the engine and the stem I from the governor of the engine, as hereinafter more fully described.

The upper end of the hollow stem H is provided with a hexagonal nut H', fitting into a 65 correspondingly-shaped recess in a plate H², secured to the top of the main valve F, so that when the said hollow stem H is turned a like motion is given to the main valve F. The other stem I is provided with pins I', extending through slots H³, cut in the hollow stem H and engaging the cut-off valve G, so that when the stem I is turned a like motion is given to the cut-off valve G without carrying the stem H along, as the pins I' pass loosely 70 through the slots H³.

The main valve F is provided with inlet-ports g and h, adapted to register with the ports d and e, respectively, leading to the cylinder-ports to admit steam alternately to the 80 ends of the cylinder. The ports g and h are also adapted to register with openings D' D², formed on opposite sides of the valve-body D, so that live steam from the steam-chest can pass through the said openings and the 85 corresponding port g or h to the end of the cylinder to act on the piston therein in the usual manner. The ports g and h when connected with the corresponding port d or e are controlled by the cut-off valve G, and for this 90 purpose the main valve F is provided with additional ports j and k, adapted to register with ports l and n, respectively, formed in the cut-off valve G to connect the ports j and g with each other by the port l and to connect 95 the ports k and h with each other by the port n. The main valve F is also provided between the ports g and h with a cavity i for connecting the ports d and e with the port f, leading to the exhaust-port c. 100

As shown in Fig. 2, the cut-off valve G has just cut off the port g from the port j, so that live steam is cut off from the left-hand end of the cylinder, while the cavity i still con-

nects the ports *e* and *f* with each other to allow the steam at the right-hand end of the cylinder to pass to the exhaust-port *c* and out of the exhaust-pipe *E*². The port *k*, as shown in the said figure, is cut off at the front portion *D*³ of the valve-body *D* adjacent to the opening *D*²; but when a rocking motion is given to the main valve *F* then the port *h* moves in register with the port *e* and the port *k* moves into the opening *D*², while the port *j* is cut off from the front *D*³, while the other port *g* opens into the opening *D*¹, and the cavity *i* connects the ports *d* and *f* with each other. Steam cannot pass through the port *h* to the ports *e* and *b* at the right-hand end of the cylinder *A* until the cut-off valve *G* has moved its port *n* in such a position as to register with the ports *h* and *k*.

An oscillating motion is given to the main valve *F* in the following manner: Near the lower end of the hollow valve-stem *H* is secured a segmental bevel gear-wheel *J* in mesh with a segmental bevel gear-wheel *J'*, fulcrumed on a stud *J*², carried by the cover *E*³ for the steam-chest. The upper end of the segmental gear-wheel *J'* is formed with an alined slot *J*⁵, in which is adjustably held a pivot *K'*, engaged by the eccentric-rod *K*² of the eccentric on the main shaft *C*, so that when the engine is in motion the said eccentric will impart a swinging motion to the bevel gear-wheel *J'*, which transmits its motion by the segmental bevel gear-wheel *J* to the stem *H*, so as to rock the same, and consequently the main valve *F*, with which the stem is connected. By the arrangement described an oscillating motion is given to the main valve *F* to alternately bring its ports in the position above described.

In order to impart a rocking motion to the cut-off valve *G*, I provide the following device: On the lower end of the stem *I* for the said cut-off valve is secured a segmental bevel gear-wheel *L* in mesh with a similar gear-wheel *L'*, mounted to turn on a stud *L*², carried by the engine-frame, as plainly indicated in Fig. 4. A sudden rocking motion is given to the segmental gear-wheel *L'*; but the latter, as well as the gear-wheel *L*, the stem *I*, and the cut-off valve *G*, is immediately returned to a normal position (shown in Fig. 2) by the action of the springs *L*⁴ and *L*⁵, connected with the outer ends of the arms *L*² and *L*³, extending in opposite directions from the stem *I* and at a right angle to the segmental gear-wheel *L*, as is plainly shown in the drawings. The outer ends of the springs *L*⁴ *L*⁵ are connected with nuts *L*⁶, each fitted to slide in a guideway *L*⁷, carried by the steam-chest, the nut being engaged by a screw *L*⁸, screwing in the guideway, to move the nut forward or backward and increase or decrease the tension of the spring *L*⁴ or *L*⁵. On the front face of the segmental gear-wheel *L'* is secured or formed a lug *L*⁹, in the upper end of which is pivoted a tooth *N*, adapted to be engaged by a friction-roller *O*, journaled in the lower end

of a cut-off arm *O'*, extending on the front face of the segmental gear-wheel *J'* and formed with alined slots *O*² *O*³, through the latter of which passes a bolt *O*⁴, carried by the segmental gear-wheel *J'*. The upper end of the cut-off arm *O'* is pivotally connected with a link *P*, fitted to slide loosely in a bearing *P'*, mounted to turn on the steam-chest, the upper end of the said link being pivotally connected with the arm *Q'* of a bell-crank lever *Q*, connected at its other arm *Q*² with a link *R*, connected with a bell-crank lever *S*, having one arm engaged by the sleeve of a governor *T*, so that the action of the latter imparts a swinging motion to the bell-crank lever *S*, and this motion is transmitted by the link *R* to the bell-crank lever *Q*. The motion of the latter causes the link *P* to impart a sliding motion upward or downward to the arm *O'*, so that the latter, which rocks with the bevel gear-wheel *J'*, moves the tooth *N* a greater or shorter distance to the right or left to give more or less rocking motion to the segmental gear-wheel *L'* and to the segmental gear-wheel *L*, the stem *I*, and the cut-off valve *G*. The tooth *N* is provided on opposite sides with curved arms *N*¹, over which the friction-roller *O* travels, the tooth, with its arms, being fulcrumed at *N*² on a lug *L*⁹, and the said arms are pressed on by springs *N*³, carried by the said lug, so as to permit the arms to yield when the friction-roller *O* comes in contact with the same to guide the friction-roller to the tooth *N*, the arms being always in contact with the friction-roller to avoid the noise which would otherwise occur on the roller striking the tooth without being guided.

From the foregoing it is evident that the rocking motion given to the main valve *P* is uniform, while that given to the cut-off valve varies with the speed of the engine, so that the valve cuts off sooner when the engine runs at a high speed and later when the speed decreases, so as to admit more steam to the corresponding end of the cylinder. Both valves *F* and *G* are provided with suitable packing-plates, as indicated in the drawings, to prevent leakage of steam.

The valve described can be readily applied to an ordinary engine by removing the steam-chest cover and slide-valve and substituting the new and improved valve and replacing steam-chest cover and making the proper connection with the eccentric-rod and the governor. The valve is completely balanced, as the steam-pressure is equally divided both inside and outside of the main valve and the cut-off valve contained in the main valve.

As the main valve and the cut-off valve receive positive motion from different sources and move wholly independently of each other, but in the same direction, it is evident that the cut-off valve can move with the main valve up to the point of cut-off and then rapidly close the main valve to prevent steam from passing to the end of the cylinder. As the valve has little or no lap, it will open

readily and admit the greatest amount of steam in the shortest time with a quick cut-off to insure a proper expansion of the steam, and thus utilize the steam admitted to the 5 fullest advantage.

By having an adjustable connection between the eccentric-rod K² and the segmental gear-wheel J' the main valve can be readily set to any desired stroke.

10 The cut-off valve can be set stationary to cut-off or can be worked loose from the governor on pins constructed for that purpose, and it cuts off according to the variations of the load of the engine, thus making the valve 15 a strictly automatic cut-off valve.

By the use of the springs L⁴ and L⁵, connected with the arms L² L³ on the cut-off valve-stem I, the cut-off valve is not liable to jump ahead of the port and is compelled to 20 close correctly, as both springs pull toward a straight line extending through the center of the arms. The cut-off valve by the action of the arm O', traveling with the segmental gear-wheel J' and acting at the same time on the 25 tooth N, admits steam to the cylinder until the point of cut-off is reached, and the friction-roller O in releasing the tooth N permits the springs L⁴ L⁵ to instantly snap to their normal positions and cause the cut-off valves 30 to do the same and in a direction inverse to that of the main valve, so as to insure the rapid cut-off previously mentioned.

The main valve F rests with its lower end on a suitable step E³, carried by the steam-chest E, and the valve-stem I is set at its 35 lower end in a step on the engine-frame.

Having thus fully described my invention, I claim as new and desire to secure by Letters Patent—

40 1. A steam-engine comprising a hollow main valve, a gearing controlled from the eccentric and connected with the main valve to oscillate the same, a cut-off valve mounted to oscillate within the hollow main valve, a gearing for the same and means controlled by the 45 governor for actuating the cut-off-valve gearing, substantially as shown and described.

2. A steam-engine valve comprising a main valve, gearing controlled from an eccentric 50 for oscillating the said valve, a cut-off valve for the said main valve, gearing for the cut-off valve, means for actuating the gearing of the cut-off valve to oscillate the said cut-off valve with the main valve until the cut-off 55 point is reached, and means for suddenly returning the said cut-off valve to a normal cut-off position, substantially as described.

3. A steam - engine valve, comprising a valve-body having openings leading into the 60 steam-chest and ports connected with the cylinder-ports, a main valve mounted to turn in the said valve-body and having ports for registering with the said openings and the said ports in the valve-body, the said main valve 65 being hollow, and a cut-off valve mounted to oscillate in the said hollow main valve to cut off the ports therein from the steam-supply, a

segmental gear-wheel on the stem of the cut-off valve, the said gear-wheel being in mesh with a similar gear-wheel mounted to turn on 70 the engine-frame, and means controlled by the governor for rocking the latter gear-wheel, substantially as shown and described.

4. A steam - engine valve, comprising a valve-body having openings leading into the steam-chest and ports connected with the cylinder-ports, a main valve mounted to turn in the said valve-body and having ports for registering with the said openings and the said ports in the valve-body, a segmental gearing 80 connected with the main valve to oscillate the same and controlled from a moving part of the engine, a cut-off valve mounted to oscillate within the said main valve to cut off the ports therein from the steam-supply, and 85 means for operating the said cut-off valve independently of the main valve as set forth.

5. A steam-engine valve comprising a valve-body having openings leading into the steam-chest, and ports connected with the cylinder-ports, a main valve mounted to turn in the said valve-body and having ports for registering with the said openings and the said ports in the valve-body, the main valve being hollow, a cut-off valve mounted to oscillate in 95 the said hollow main valve, to cut off the ports therein from the steam-supply, a segmental gearing controlled from the eccentric of the engine and connected with the main valve to oscillate the same, a spring connection for the 100 cut-off valve, to quickly return the latter to a normal cut-off position, and means carried by the said segmental gearing for oscillating the said cut-off valve with the main valve until the cut-off point is reached, substantially as shown and described.

6. A steam-engine valve provided with a main valve, a segmental gearing controlled from an eccentric, for oscillating the said valve, a cut-off valve for the said main valve, 110 a gearing for the said cut-off valve, springs for suddenly returning the cut-off valve to a normal cut-off position, and an arm moving with the said main-valve gearing and adapted to actuate the cut-off-valve gearing up to the 115 point of cut-off, substantially as shown and described.

7. A steam-engine valve provided with a main valve, a segmental gearing controlled from an eccentric for oscillating the said 120 valve, a cut-off valve for the said main valve, a gearing for the said cut-off valve, springs for suddenly returning the cut-off valve to a normal cut-off position, and an arm moving with the said main-valve gearing and adapted 125 to actuate the cut-off-valve gearing up to the point of cut-off, the said arm being slidable on the said main-valve gearing and under the control of the governor, substantially as shown and described.

8. A steam-engine valve comprising a hollow main valve having a hollow-stem connection within the main valve, and connected with the end thereof, a hollow cut-off valve

mounted to turn on the said stem within the hollow main valve, and a cut-off-valve stem within the hollow main-valve stem, and having pins extending through slots in the latter stem and engaging the cut-off valve to oscillate the latter independently of the main valve, substantially as shown and described.

9. A steam-engine valve comprising a hollow main valve having a hollow-stem connection within the main valve, and connected with the end thereof, a hollow cut-off valve mounted to turn on the said stem within the hollow main valve, a cut-off-valve stem within the hollow main-valve stem, and having pins

extending through slots in the latter stem and 15 engaging the cut-off valve to oscillate the latter independently of the main valve, means connected with the main-valve stem for oscillating the main valve, and means connected with the cut-off-valve stem for oscillating the 20 cut-off valve, substantially as shown and described.
